UNITED STATES PATENT OFFICE.

OBADIAH SEELY, OF SYRACUSE, NEW YORK.

SPRING-HINGE.

SPECIFICATION forming part of Letters Patent No. 438,115, dated October 7, 1890.

Application filed November 16, 1888. Serial No. 291,011. (Model.)

To all whom it may concern:

Be it known that I, OBADIAH SEELY, of Syracuse, county of Onondaga, in the State of New York, a citizen of the United States, 5 have invented certain new and useful Improvements in Hinges, of which the following is a specification, reference being had to the accompanying drawings, in which—

Figure I is a top plan or face view of the 10 hinge. Fig. II is a vertical sectional elevation thereof, showing the construction of the pintles and the ears upon the leaves and the tension-lock. Fig. III is an end elevation showing the lock in the outer ear. Fig. IV is 15 a like view with the lock in inner ear. Fig. V is an elevation of a pindle detached.

My invention relates to spring-hinges for doors, and to that class in which a coil is mounted substantially upon the central vertical line of the hinge, and upon which a torsion tension is produced by the opening of the door to which the hinge is attached, the torsion being sufficient to close the door again.

The object of my invention is to produce a 25 spring-hinge in which the spring occupies substantially the position of the ordinary pindle-bearing in a hinge, and which is connected to tension-adjusting devices or pins, which also operate as the pintles of the hinge.

30 My invention consists in the several novel features of construction and operation hereinafter described, and which are specifically set forth in the several clauses of claim hereto annexed.

35 It is constructed as follows: The hinge consists of the leaves 1 and 2, which may be of any form or of any style of ornamentation, each leaf being provided with ears 3, 4, 7, and 8, standing at right angles to the plane 40 of the leaves and of the pintles 5 and 6. The ears 3 and 4 stand upon the leaf 1, and 7 and 8 upon the leaf 2. The pindle 5 passes through the ears 7 and 3, and the pindle 6 through ears 4 and 8. All of the ears are perforated 45 to receive the pindle, and, as shown in the drawings, the perforations through the ears 4 and 7 are circular and the perforations through the ears 3 and 8 are hexagonal, though

they may be of any other angular form. The pintles are substantially alike in construction. 50

The pindle 6 consists of a cylindrical stem having an angular periphery 10 fitting the angular ear-perforations and a circular bearing 9, a head 11, and a stem 12, and the head 11 is also grooved in the edge, as at 13, to receive the end of the spring rod or wire and hold it. In the drawings I show the pindle 5 as slightly differing in the detailed construction in that in 5 the angular portion 10 is next to the head 11, and in the ends of the pintles 55 I make the screw-driver slots 14.

It will be observed, first, that this hinge is capable of being used for either a right or a left hand hinge; second, that when I desire to adjust or impart tension to the spring I, 65 for instance, insert the screw-driver into the slot in the pindle 5, push the whole pindle inwardly until the angular portion 10 is inside of the ear 3, and I then, holding the pindle in that position, turn the pindle around, twisting the coil of the spring B, which is mounted between the pintles, until I get the desired 70 tension, and by twisting the pindle to the right the door will swing to the left through the spring action, and, third, that the tension can 75 be adjusted by operating either pindle.

What I claim as my invention, and desire to secure by Letters Patent, is—

In a spring-hinge, the combination of the leaves 1 2, provided, respectively, with ears 3 80 4 and 7 8 adjacent to their ends, the ears 4 and 7 being provided with circular pindle-holes and the ears 3 and 8 with angular pindle-holes, pintles provided with circular bearings fitting the circular ear-holes, and angular bearings fitting the angular ear-holes of said ears, and a spring inserted between the pintles and held in place thereby, substantially as and for the purpose set forth. 85

In witness whereof I have hereunto set my 90 hand this 10th day of November, 1888.

OBADIAH SEELY.

In presence of—

HOWARD P. DENISON,
C. W. SMITH.
